[57] CLAIM

The ornamental design for a beverage container, as shown and described.

DESCRIPTION

FIG. 1 is a perspective view of a beverage container showing my new design;

FIG. 2 is side elevational view from a corner of the beverage container as shown in FIG. 1, the opposite side being a mirror image thereof;

FIG. 3 is a front elevational view of the beverage container thereof;

FIG. 4 is a rear elevational view of the beverage container thereof;

FIG. 5 is a top plan view of the beverage container thereof; and,

FIG. 6 is a bottom plan view of the beverage container thereof.

The broken lines showing thread around the neck in FIGS. 1 through 5 of the drawing are for illustrative purpose only and do not for part of the claimed design.
